SAFETY RAZOR

Filed May 13, 1931

UNITED STATES PATENT OFFICE

JOSEPH MUROS, OF NEW YORK, N. Y., ASSIGNOR TO GILLETTE SAFETY RAZOR COMPANY, OF BOSTON, MASSACHUSETTS, A CORPORATION OF DELAWARE

SAFETY RAZOR

Application filed May 13, 1931. Serial No. 536,979.

An object of my invention is to provide means, such as an adapter, to be applied to a safety razor to locate a blade in shaving position thereon which otherwise would not fit properly in the razor, as distinguished from a proper blade made to fit the razor.

A further object of my invention is to provide such an adapter that will not only locate a blade in shaving position in the razor but may also control the position of the blade cap or blade backing member of the razor with relation to the guard member thereof. This feature of my invention is particularly applicable in safety razors having blade clamping members in which the blade cap or backing member and the guard member do not have cooperative means for locating the cap in shaving relation to the blade, as in those razors in which the blade itself cooperates with the cap or backing member to locate the latter in shaving relation to the blade and the guard member does not serve for such purpose.

In carrying out my invention I provide a safety razor comprising blade clamping members and means to retain said members clamped against a blade, with an adapter provided with means to detachably connect it with one of said members, such as the guard member, said adapter and the cap or blade backing member having cooperative means a blade to retain the latter in shaving relation to a blade between said members, said adapter also having means to cooperate with a blade to retain the latter in shaving relation to the guard member, although said blade may not have means cooperative with the guard member itself for positioning the blade thereon.

My invention also comprises novel details of improvement that will be more fully hereinafter set forth and then pointed out in the claims.

Reference is to be had to the accompanying drawing wherein:

Fig. 1 is an edge view of a safety razor embodying my invention;

Fig. 2 is a section on line 2, 2, in Fig. 1;

Fig. 3 is a perspective view of my improved adapter to be attached to a member of the

blade holder of the safety razor for locating a blade in shaving position;

Fig. 4 is a perspective view of a blade to be retained by the adapter;

Fig. 5 is a plan view illustrating the adapter on the guard member, and a portion of the blade;

Fig. 6 is an inverted face view of the blade cap or backing member;

Fig. 7 is a section on line 7, 7, in Fig. 2; and

Fig. 8 is a section on line 8, 8, in Fig. 1.

Similar numerals indicate corresponding parts in the several views.

The blade clamping members, as indicated, include a guard member 1 and a cap or blade backing member 2 adapted to clamp a blade 3 between them. Any suitable means may be provided for clamping the members 1 and 2 against the blade. I have illustrated the cap 2 as provided with a threaded stem 4 adapted to pass through an opening 1b in the guard member, and to mesh in the threaded recess 5 in the handle 6 for detachably clamping the members against the blade. My improved adapter for blades is indicated at 7, and comprises a piece of suitable metal shaped to rest against the guard member 1, between the latter and the cap 2, and provided with an opening 7a shown in the form of a longitudinally disposed slot, and wide enough to allow projections 10 of the guard member 1 to pass freely through said opening 7a. I have shown the adapter 7 as provided with marginal portions 8 adapted to extend along 80 and engage the outer surfaces of the guard teeth 1a of the guard member 1 for positioning the adapter on said member. The marginal portions 8 of the adapter may be curved 85 in such a way as to partially enclose or underlie the edges of the guard teeth to retain the adapter on the guard member from lateral lifting or displacement therefrom, the end portions of the adapter being shown open 90 whereby the latter may be slid lengthwise 95 along the inner or blade-engaging surface of the guard member. The marginal portions 8 of the adapter are shown provided with longitudinal slots 9 that register with the guard teeth whereby lather from shaving may pass 100

through said apertures to and between the guard teeth.

Blade clamping members of the character set forth are customarily provided with means to locate and retain a proper blade in shaving relation to such members. The clamping members 1 and 2 may be provided with any desired means for positioning the blade for shaving in conjunction with a proper blade. I have illustrated the guard member

10 member as provided with projections 10, spaced apart on opposite side of a hole 1b in the

guard member, said projections being adapted to fit and cooperate with a proper blade, made for the blade holder illustrated, for re-

15 taining said blade in shaving relation to the guard teeth. The blade 3, as illustrated, is provided with an opening 3a, shown in the form of a longitudinally disposed slot, which will not properly fit the projections 10 of the

20 guard member and therefore would be loose and not be retained in proper shaving position between the clamping members. My im-

25 proved adapter is designed to locate the said blade 3 in proper shaving position between the clamping members irrespective of the character of the opening 3a of a blade that does not fit the projections 10. I have shown

30 the adapter 7 as provided at its ends with outwardly extending projections 11 that are adapted to cooperate with the ends of the

35 blade to retain the latter in shaving position with respect to the guard member. By pref-

40 erence the blade is shown provided with projecting means 3b at its ends that are lo-

45 cated in spaced relation by means of recesses 3' at the ends of the blade. When the adapter is in position on the guard member and the

50 blade 3 is applied against the adapter, the

55 projections 10 will not properly fit the blade in its opening 3a but the projections 3b of

60 the blade will engage the projections 11 of

65 the adapter, and thereby the blade will be lo-

70 cated in shaving relation to the guard teeth.

45 In the example illustrated, it will be as-

50 sumed that the projections 10 of the guard member do not fit against the cap or blade

55 backing member 2 so as to locate the latter in shaving relation to the blade. As illus-

60 trated, the cap 2 is shown provided in its under surface with recesses 12 that receive the projections 10 loosely so as not to guide or control the operative position of the cap. The cap, however, is provided with means

65 to cooperate with the adapter to locate and retain the cap in shaving relation to the blade. I have shown the cap as provided

70 with projections 13 at its corners that extend toward the adapter to engage the latter,

75 whereby the adapter will position the cap with its longitudinal edges in proper shav-

80 ing relation to the cutting edges of the blade. I have shown the adapter as provided at its

85 ends with recesses 14 adapted to receive the

90 projections 13 of the cap for properly locat-

ing and retaining the latter in position on the adapter. The blade is shown provided with recesses 3'' at its corners, that register with the recesses 14 of the adapter to permit the projections 13 of the cap to pass through the recesses 3'' to enter the recesses 14 of the adapter, (see Figs. 1 and 8). The adapter, therefore, constitutes a means, when applied on the guard member, for retaining the cap in proper shaving position on a blade that otherwise would not fit properly in the blade holder.

The recesses 3'' at the corners of the blade may be of such an area as not to engage the lugs 13 of the cap although said recesses 3'' may be of such dimensions as to engage said projections 13 and thereby the blade may position, or assist in positioning, the cap in shaving position on the blade. The guard member is shown provided with spaced re-

85 cesses 15 which may extend all along the

guard member in a longitudinal direction

90 into which the projections 13 of the cap may

freely extend so as not to interfere with the

clamping of the blade and the adapter be-

95 tween the members 1 and 2.

When the blade holder is used with a proper blade to fit the projections 10 of the guard member, the projections 13 of the cap may

95 engage such proper blade to cause the blade to position the cap thereon for shaving in a well-known way. If, however, it is desired

100 to use the blade holder described with a blade that does not properly fit the same, such as blade 3, the user will apply the adapter on

105 the guard member and he may then place the blade 3 on the adapter which will locate the

110 blade in shaving relation to the guard, and then by applying the cap upon the blade the adapter will locate the cap in shaving posi-

115 tion on the blade, so that when the parts are clamped together, by the stem and the han-

120 dle, the blade will be properly retained for

125 shaving.

Changes may be made in the details of

130 construction set forth within the scope of the

appended claims without departing from the

spirit of my invention.

Having now described my invention, what

135 I claim is:

1. An adapter for a safety razor having oppositely disposed downturned edges to locate it in operative position on a member of a safety razor, said adapter having means to cooperate with a different member of the razor to locate said member in shaving relation to a blade in the razor.

2. An adapter for a safety razor having oppositely disposed downturned edges to locate it in shaving position on a guard member of the safety razor, said adapter having means to cooperate with a cap member of the razor to position the cap member in shaving relation to the guard member.

3. An adapter for a safety razor provided

with oppositely-disposed, down-turned edges to locate it in shaving position on a guard member, said adapter having an opening to receive projections from said guard member, 5 said adapter being provided with means to position a blade narrower than said guard on the adapter in shaving relation to the guard member.

4. An adapter for a safety razor provided 10 with means to engage the guard teeth of a guard member of a razor, said adapter having an opening to receive blade locating means of said razor, the adapter being provided with projections at its ends to engage a blade thereon to locate the latter in shaving position on the adapter.

5. An adapter as set forth in claim 4 provided with recesses at its ends to receive projections from the cap.

20 6. An adapter for a safety razor comprising a piece of metal having curved marginal portions to enclose guard teeth of a safety razor for locating the adapter on said member in shaving position, said adapter having 25 means to engage a blade to locate the latter in shaving position on the guard member.

7. An adapter as set forth in claim 6 having recesses at its ends to engage projections from the cap of the razor.

80 8. An adapter for a safety razor comprising a piece of metal having curved marginal portions to enclose guard teeth of a safety razor for locating the adapter on said member in shaving position, said adapter having 85 means to engage a cap to locate the latter in shaving position on the adapter.

9. A safety razor comprising blade clamping members, one of said members having 40 projections to locate a blade in shaving position with respect to said member, an adapter having curved longitudinal edges to engage said member to position the adapter thereon, a blade having an opening to loosely receive 45 said projections, the adapter having means co-operative with the blade to locate the latter in shaving position on the adapter, and means to clamp said members with the blade and the adapter between them.

10. A safety razor as set forth in claim 50 9 in which the adapter is provided with means to engage the other member of the razor to locate the latter in shaving position on the blade.

55 11. A safety razor comprising a guard with marginal teeth, a cap, an interposed blade, and an adapter having blade-locating means and downturned edges arranged to engage the teeth of the guard, and a long slot in each downturned edge disposed adjacent to the 60 guard teeth.

JOSEPH MUROS.
